[57] CLAIM

The ornamental design for a combined plate and frame stand, substantially as shown and described.

DESCRIPTION

FIG. 1 is a perspective view of a combined plate and frame stand showing our new design;

FIG. 2 is a front elevational view;

FIG. 3 is a rear elevational view;

FIG. 4 is a side elevational view;

FIG. 5 is a top plan view; and

FIG. 6 is a bottom plan view.

The side not shown is a mirror image of the side shown in FIG. 4.

FIG. 11FIG. 22FIG. 3FIG. 44FIG. 5FIG. 6
